UNITED STATES PATENT OFFICE

162,347

PRINTING PRESS

Viktor Schreckengost, East Cleveland, Ohio, assignor to Harris-Seybold Company, Cleveland, Ohio, a corporation of Delaware

Application November 1, 1950, Serial No. 12,802

Term of patent 14 years

(Cl. D64—11)

To all whom it may concern:

Be it known that I, Victor Schreckengost, a citizen of the United States, residing at East Cleveland, county of Cuyahoga, and State of Ohio, have invented a new, original, and ornamental Design for Printing Press, of which the following is a specification, reference being had to the accompanying drawing forming a part thereof, in which:

Fig. 1 is a side perspective view of a printing press showing my new design from the sheet delivery end of the press, the essential features being shown in full lines.

Fig. 2 is a view in perspective of the opposite side of the machine.

I claim:

The ornamental design for a printing press, as shown and described.

VIKTOR SCHRECKENGOST¹
